UNITED STATES PATENT OFFICE.

HERBERT B. WYCKOFF, OF CINCINNATI, IOWA.

CONVEYER.

1,180,456.

Specification of Letters Patent.

Patented Mar. 2, 1915.

Application filed January 11, 1908. Serial No. 471,719.

To all whom it may concern:

Be it known that I, HERBERT B. WYCKOFF, a citizen of the United States, residing at Cincinnati, in the county of Appanoose and State of Iowa, have invented a certain new and useful Conveyer, of which the following is a specification.

The object of my invention is to provide a device of simple, durable and inexpensive construction, designed to be operated by power from an engine for the purpose of loading railway cars with cinders, stones, or similar material.

More specifically, it is my object to provide a device of this kind that may be readily, quickly and easily moved by hand from place to place relative to a pile of material to be loaded so that the material may be readily and easily placed on the receiving end of the conveyer.

A further object is to provide a conveyer especially adapted for use in connection with loading cinders, stones and the like, and so arranged that large objects in the material to be loaded will not move rearwardly and downwardly by gravity over the loader while being conveyed.

A further object is to provide an improved conveyer so arranged that the material being loaded will not fall between the buckets and cross slats of the conveyer, nor between the sides of the buckets and the sides of the conveyer frame.

My invention consists in the construction, arrangement and combination of the various parts of the device whereby the objects contemplated are attained, as herein-after more fully set forth, pointed out in my claims and illustrated in the accompanying drawings, in which—

Figure 1 shows a side elevation of a conveyer embodying my invention with parts of the housing broken away to show certain details of construction. Fig. 2 shows a similar view illustrating the receiving end of the loader with parts broken away to show details of construction, said view when considered in connection with Fig. 1 shows the complete machine. Fig. 3 shows a top or plan view of the complete device with the roof of the engine house and the receiving end of the conveyer broken away. Fig. 4 is a plan view of the receiving end of the conveyer. Said view is intended to be considered in connection with Fig. 3. Fig. 5

is a detail perspective view of one of the cross slats of the conveyer and a bucket thereon. Fig. 6 is a detail sectional view taken on the line 6—6 of Fig. 2. Fig. 7 is a detail taken on the line 7—7 of Fig. 1 and also illustrating a slight modification in one of the sides of the conveyer frame. Fig. 8 is an enlarged plan view, illustrating a portion of the conveyer with part of the buckets and cross slats broken away to show the conveyer links. Fig. 8^a is an enlarged end view, illustrating a cross slat and bucket in position on the conveyer chain with a part of the cross slat and other parts broken away. Fig. 9 is an enlarged central sectional view through the conveyer buckets and cross slats with the conveyer links connected with the cross slats. Fig. 10 is a side view of one of the conveyer links; and Fig. 11 is a top or plan view of the same.

In the drawings reference numeral 10 has been used to indicate the base-frame of the conveyer. At the forward end of this base-frame are two longitudinal shafts 11, each of which has rotatably and slidably mounted thereon a flange wheel 12 designed to rest upon a track rail 13. At the rear end of the base-frame 10 are the shafts 14, having supporting wheels 15 rotatably and slidably mounted thereon. In this way the base is supported upon four wheels, two of which are loosely mounted on their shafts and rest upon a track rail and two of which rest on the ground.

Arranged upon the base-frame 10 is a housing 16 designed to cover the engine and gearing devices hereinafter described. Mounted upon the frame 10 is an upright frame 17 which is supported in position by means of the braces 17^a on the frame 10. 95 Guy rods 18 are attached at one end to the rear or receiving end of the conveyer and at the other end to said upright frame 17. Mounted upon the frame 10 is an engine 19 which is connected by means of a belt 20 with a pulley 21 on a shaft 22. The various operative parts of the conveyer are geared to this shaft 22, as will hereinafter appear.

The conveyer frame is clearly illustrated in Fig. 6 and comprises two side members 23 and 24, the side 23 being somewhat higher than the side 24. A number of shafts 25, having rollers 26 thereon, connect the lower portions of the sides 23 and 24. Below the

sides 23 and 24 are the lower side members 27 and 28 which are slung from the sides 23 and 24 by the conveyer braces 23^a and 24^a. The sides 27 and 28 each carry a number of short shafts 29 on which rollers 30 are mounted.

The conveyer links, as clearly shown in Figs. 10 and 11, are each composed of a body portion 31, having at one end a rounded lug 32 and at the other end two rounded lugs 33, the lug 32 being designed to enter between the lugs 33 of an adjacent link. All of said lugs are perforated to receive pivot pins.

Secured to each pair of links is a cross slat 34 and on the lower faces of the links are the track portions 35 designed to rest on top of the rollers 26, as clearly shown in Fig. 6. Secured to each of the adjacent cross slats 34 is a conveyer bucket comprising a flat bottom 36. The forward edge of each bucket is spaced behind the adjacent edge of the cross slat and the rear edge of each bucket projects over the rear edge of the cross slat. Each conveyer bucket also comprises two upright side members 37 and an upright front 38. In Fig. 9 of the drawings I have shown an arrangement of these bucket fronts, which is an important feature of my invention. This arrangement consists in providing a number of bucket front members 38 adjacent to each other and having a height about one-half that of the sides of the bucket, though at certain intervals throughout the length of the conveyer I provide bucket fronts 39 of materially greater height. The object of this feature of construction will be set forth hereinafter in connection with the description of the forward conveyer section.

For operating the rear conveyer section by power from the engine, I have provided a shaft 40 mounted on the frame 10 and connected with the shaft 22 by means of the pinions 41 and 42. On the other end of the shaft 40 is a sprocket wheel 43 connected by a sprocket chain 44 with a sprocket wheel 45 on a shaft 46, the latter being mounted on the frame of the forward conveyer, as will hereinafter appear. On this same shaft 46 is a sprocket wheel 47 connected by a sprocket chain 48 with a sprocket wheel 49, the latter being fixed to a shaft 50 around which the rear conveyer section turns.

The forward conveyer section comprises an upper side member 51 and a lower side member 52, similar to the side members of the rear conveyer section before described. The shaft 46 is extended through the rear end of the side member 51 and forms a pivot on which said conveyer section may be raised or lowered.

I provide for driving the forward conveyer section as follows: On the shaft 46 which is mounted on the braces 17^a is a

sprocket wheel 53 connected by a sprocket chain 54 with a sprocket wheel 55 on a shaft 56 at the upper end of the conveyer section.

To provide for raising and lowering the forward conveyer section, I attach the rod 57 with a hook 58 at the top of the upright 17 by means of the pulleys 59 and 60 and the rope 61. This rope has one end fixed to and wound upon a windlass 62 on the upright 17. I have also provided means for preventing material that is being carried by the conveyer from falling between the ends of the buckets and sides of the conveyer frame, as follows: On each of the sides of the conveyer frame is a shield 63 which extends downwardly to a point below the bucket sides 37 and to points adjacent to the inner surfaces of said sides 37, as clearly appears in Fig. 6. Inasmuch as these bucket sides are higher than the front portions of the buckets, these shields will not in any way interfere or engage with the buckets.

It is obvious that when the forward conveyer section is at an angle approaching the vertical, stones or large cinders thereon are likely to fall rearwardly, and in order to prevent them from striking upon the rear conveyer section I have provided a curved sheet metal plate 64 pivoted to the upright 17 with its forward end adjacent to and resting upon the frame of the forward conveyer. This plate will be engaged by any such falling stones or cinders and thus the rear conveyer section will be protected.

In practical use and assuming that it is desired to convey a quantity of cinders, or the like, from a pile to a railway car, the operator first moves the machine until the side 24 is close to the bottom of the pile of cinders, then the cinders from the pile may be readily and easily moved to the buckets at the receiving end of the rear conveyer section. When this is being done, the side 23 forms a side-board to prevent the cinders from falling over the conveyer. Material thus placed upon the rear conveyer section will be carried by the buckets and discharged upon the rear end of the forward conveyer section. None of this material can fall out of the buckets for the reason that the shields 63 prevent it from falling out over the ends of the buckets, and the bottoms of the buckets by projecting over the spaces between the cross slats 34, prevent all of said material from falling down between the buckets.

When the material is thus discharged upon the rear end of the forward section, it will be conveyed by the forward section to the upper or discharge end thereof and will be loaded upon a car. By having the forward ends of the buckets arranged as shown in Fig. 11 with a number of them of greater height than the others, it is obvious that large cinders or clinkers or other large bodies will be held

within the buckets and prevented from falling downwardly by gravity in a direction opposite from the direction in which the buckets are moving.

5. By having the wheels 12 arranged so that they slide longitudinally upon their shafts, the conveyer frame may be conveniently and easily moved to make the receiving end readily accessible to the operator who is 10 loading the conveyer.

The forward end of the forward conveyer section may be raised or lowered to the desired elevation by means of the windlass 62 and when said forward conveyer is 15 at a considerable degree of elevation and in the event that large cinders or stones should be in position on the conveyer buckets and should start to fall downwardly in a direction opposite from the direction of 20 movement of the conveyer, then said cinders or stones or the like would strike upon the curved plate 64 and thus be prevented from injuring the buckets of the rear conveyer section.

25. I claim as my invention.

1. In a device of the class described, the combination of a series of cross slats pivotally connected with each other, and a series of buckets of uniform width, one bucket 30 being fixed to each cross slat, the forward walls of said buckets being positioned in the rear of the forward edges of the slats, and the rear edges of the buckets being projected beyond the rear edges of the slats so that 35 the bottoms of said buckets overlap the spaces between the slats.

2. In a device of the class described, the combination of a series of links, a cross slat

fixed to the body portion of each of said links, a bucket on each of said cross slats, 40 comprising a bottom with its rear edge projected beyond the rear edge of the slat and its forward edge spaced apart from the forward edge of the slat, and also comprising two upright side members lying in alignment with the successive upright side members, and an upright front member lower than said side members.

3. In a device of the class described, the combination of a series of cross slats, a 50 bucket fixed in an offset position on each cross slat, each bucket having an upright front member, some of said front members being higher than others for the purposes stated, the side members extending above 55 the front members.

4. In a device of the class described, the combination of a boom, a conveyer pivoted near the base of the boom, adjusting means for raising and lowering the other end of the conveyer, an integral member pivotally mounted to the boom and swinging in conformity to the raising or lowering of the conveyer, said member resting on said conveyer frame and slipping along the same 60 when the conveyer is raised and lowered, said member being spaced somewhat above the conveyer buckets and being concaved to form a receptacle for holding material 65 which may roll down over the conveyer buckets when working at a steep inclination. 70
